UNITED STATES PATENT OFFICE.

WILLIAM D. FERRIS, OF STERLING, ILLINOIS, ASSIGNOR TO FRANTZ MANUFACTURING CO., OF STERLING, ILLINOIS, A CORPORATION OF ILLINOIS.

LATCH.

Application filed January 18, 1926. Serial No. 81,933.

This invention relates to latches for doors or windows or other closures.

Generally stated, the object of the invention is to provide a novel and improved construction and arrangement whereby a spring latch mechanism, or other latch mechanism, having a pivoted latch member, is operable by a rotatable handle, whereby the door or window or other closure is latched or unlatched by simply grasping and rotating the knob or other handle.

It is also an object to provide certain details and features of construction and combinations tending to increase the general efficiency and the desirability of a latch mechanism of this particular character.

To the foregoing and other useful ends, the invention consists in the matters herein-after set forth and claimed, and shown in the accompanying drawings, in which,—

Fig. 1 is a front elevation of a swinging door or window having latch mechanism embodying the principles of the invention.

Fig. 2 is a vertical section on line 2—2 in Fig. 3.

Fig. 3 is a vertical section on line 3—3 in Fig. 2.

Fig. 4 is a horizontal section on line 4—4 in Fig. 2.

Fig. 5 is a perspective of the pivoted latch member.

As thus illustrated, the door or window sash 1 has a hole 2 bored therein to receive the sheet-metal bushing member 3, which

has a transverse pivot 4 for the swinging latch member 5, this pivot being vertical, as shown, whereby said latch member swings horizontally. This latch member has a beveled end surface 6 for engaging the strike

piece 7, which latter is suitably secured to the frame 8 of the door or window. Said latch member also has a shoulder 9 to engage the end of said strike piece 7, as shown, thereby to latch the door or window or other closure in closed position. A compression coil spring 10 is interposed between one side of the latch member 5 and the adjacent inner surface of the sheet-metal bushing member 3, thereby to yieldingly and normally

maintain the member in latching position. The outer, cup-shaped fitting 11 engages the edges of the flange 12 of the bushing member 3, as shown, and has a knob or handle 13 swiveled in the central portion thereof, as

shown. The member 5 has the upper and lower projections 14 and 15, as shown, and the inner end of the stem of the knob 13 has a cam 16 provided with a flat side for engaging the portions 14 and 15 previously mentioned. Thus, when the knob 13 is turned in one direction, the flat side of the cam 16 will bear against the portion 14, and will operate the latch member 5 about its pivot 4, and cause the shoulder 9 to disengage the strike piece 7, thereby to unlatch the door or window or other closure. Similarly, when the knob 13 is rotated in the opposite direction, the flat side of the cam 16 will then engage the lower portion 15 and operate the latch member 5 about its pivot 4 to unlatch the door or window or other closure. Each time, of course, when the knob 13 is released, after unlatching the door or window or other closure, the spring 10 will return the member 5 to latching position, and in so doing will rotate the knob 13 to normal position, so that normally the straight side of the cam 16 always stands vertically, as shown in Fig. 2 of the drawings. Screws 17, or other suitable means, inserted through the fitting 11 and the flange 12, and into the window or door 1, may be employed to hold the entire latch mechanism in position, and removal of these screws will permit easy removal of the entire mechanism.

Thus a pivoted latch member is operated by a rotary knob or handle, and the latch mechanism is thus simple and comparatively inexpensive to manufacture, and is easily operated by rotation of the knob in either direction.

It will be obvious, of course, and will be readily understood, that the latch mechanism thus provided can be used for either the top or bottom of the door or window, as well as for the side thereof, and hence the mechanism is operable with the pivot 4 arranged either vertically or horizontally, or at any angle, and the latch member 5 is operable either horizontally or vertically, or in an inclined plane, depending upon the position which the mechanism is made to occupy on the door or window or other closure. Preferably, however, the oblong knob 13 is always vertically disposed, when in normal position, and the latch mechanism will be made accordingly, so that no matter in what

position the member 5 is required to operate, the knob 13 will nevertheless always have the same position, as shown, on the door or window or other closure, when in its normal 5 position.

While it is obvious that the catch device, or latch mechanism, as shown and described, can be used for any desired purpose, it may be explained that this device is especially 10 adapted for use on cupboard doors, as it can be so applied as to latch the door either to the cupboard frame, or to one of the shelves, inasmuch as the strike piece can be fastened either to the frame or to the under side of 15 a shelf. The different parts, with the exception of the knob, may be made of steel or brass stampings, or other suitable metal, and the knob may be of metal or glass, or of any other suitable material. But the catch device, or latch mechanism, constituting the invention, is not limited to any particular use, and may be used on doors, windows, or other closures of any suitable character, without departing from the spirit of the invention.

25 It will be seen that the cam member 16 is entirely outside of the hole 2 in the door, and is in a plane between the door and the outer wall of the fitting 11, whereby this cam may be of any desired or necessary size, and 30 whereby the whole mechanism may be comparatively small and may be small enough to bring the latch member 5 close to one edge of the door, as illustrated in the drawings.

Thus the screws 17 serve to fasten the two 35 parts 11 and 12 of the mounting together, so that this mounting is unitary, the two parts thereof being directly connected or fastened together, as well as being connected through the medium of the cam and latch member. 40 Thus, when the fastening screws 17 are withdrawn, the entire mounting unit supporting the knob and cam and pivoted latch member and spring can be withdrawn from the door.

45 Without disclaiming anything, and without prejudice to any novelty disclosed, what I claim as my invention is:

1. In a spring latch mechanism for a door or window or other closure having a hole 50 therein, the combination of a pivoted latch member in said hole, a strike piece for engaging said latch member, a rotatable knob or handle, rotatable about an axis at right angles to the plane of the door, actuating means at one end of said hole and whereby rotation of said knob or handle is operative 55 to actuate said pivoted latch member, a casing comprising outer and inner metal sections fastened together to form a unitary 60 mounting for said latch member and knob and actuating means, the knob being swiveled in the outer section only, the knob and actuating means and latch member and said

sections being separable as a unit from said door.

2. A structure as specified in claim 1, comprising a bushing in said hole, forming one of said sections, in which said latch member is pivoted, said bushing having a flange at the outer end thereof, and a fitting in 70 which said knob is swiveled, forming another one of said sections, engaging the outer edge of said flange, together with means extending through both said flange and fitting and thereby removably securing 75 said entire casing to the door or window or other closure.

3. A structure as specified in claim 1, comprising a bushing in said hole, forming one of said sections, in which said latch member is pivoted, said bushing having a flange at the outer end thereof, and a fitting in 80 which said knob is swiveled, forming another one of said sections, engaging the outer edge of said flange, said actuating means comprising a cam rigid with the knob and portions on said latch member to engage said cam, said fitting being hollow and forming with said flange a closed space in 85 which said cam is disposed.

4. In a door latch mechanism, the combination of a mounting unit comprising an outer part and an inner part, the outer part being cup-like on its inner side, the inner part engaging within the outer part, having retaining means for holding the inner part in engagement with the interior of the outer part, a rotary knob swiveled only in the outer part and having its inner end provided with a swivel head disposed in the cavity of the outer portion and having a cam-like engaging portion, a latch member pivoted on said inner part and provided with means for engaging said portion, a spring carried by the inner part and engaging said latch 105 member, and a strike piece for engaging said latch member.

5. A structure as specified in claim 4, said mounting unit having holes for the insertion of screws therethrough into said door, 110 there being space between the two parts of said mounting unit for said cam portion and for said means for engaging said cam portion.

6. A structure as specified in claim 4, said outer part of the mounting being in the form of a flat disk with an inturned flange formed at its outer edge, providing space between the inside of said outer part and the outer side of the door, in which space said cam portion and said means for engaging the cam portion are disposed.

Specification signed this 14th day of January 1926.

WILLIAM D. FERRIS.
